ASSEMBLING MACHINE FOR PAIL EARS

Louis Burckle, Kansas City, Kans., assignor to
 Continental Can Company, Inc., New York,
 N. Y., a corporation of New York

Application September 2, 1933, Serial No. 688,049

10 Claims. (Cl. 113—1)

It has been a common expedient to provide an ear for a pail to which a bail is to be attached, which ear consists of two members, one of which serves as a supporting means for the bail and the other as a backing for the ear serving as a closing means therefor. The parts of the ear are connected together and are attached to the container body by forming an opening in the wall of the container body and interfolding the edge portion at the opening in the wall with the parts of the ear. The present invention has to do with a machine for assembling the parts of the ear.

An object of the invention is to provide a machine whereby the ear backs and the ear fronts may be rapidly assembled and connected so that the assembled parts may be handled as a unit.

A further object of the invention is to provide a machine of the above type with means for applying a sealing material to the ear parts, which sealing material is so placed that it will aid in the forming of a tight joint between the ear and the wall of the pail when the ear is attached thereto.

In the drawings which show by way of illustration one embodiment of the invention—

Figure 1 is a view in section showing the two parts of an ear which have been assembled preparatory to the attaching of the same together;

Fig. 2 is a view similar to Fig. 1, and showing

30 a coating applied to the ear parts, which is to serve later as a sealing means for the joint attaching the ear to the wall of the container body;

Fig. 3 is a view showing the ear front and ear back as clinched together after the coating has been applied thereto;

Fig. 4 is a view showing the ear placed in the wall of a container preparatory to the bumping of the parts for joining the ear to the container;

Fig. 5 is a view showing the parts bumped 40 and the ear attached to the wall of the container;

Fig. 6 is a plan view showing more or less diagrammatically the machine for assembling the ear parts, the applying of the coating thereto, and the clinching of the parts together;

45 Fig. 7 is a vertical sectional view through the machine on the line 7—7 of Fig. 6 and showing the feeding means for controlling the feed of the ear backs to the turret which presents said ear backs to the different stations for operation thereon, said view showing the means for stopping the machine in case of a jam;

Fig. 8 is a vertical sectional view through the machine on the line 8—8 of Fig. 6 and showing the operating means for the feed for the ear backs, and also showing the feeding means for

the ear fronts and the control whereby no ear front is fed unless there is an ear back to receive the same;

Fig. 9 is a view in vertical section on the line 9—9 of Fig. 6, and showing the means for rotating the ear parts, the means for applying the coating, and also the means for controlling the feed of the coating through the applying nozzle;

Fig. 10 is a detail showing the cam for operating the lever controlling the valve of the coating device;

Fig. 11 is a view in vertical section on the line 11—11 of Fig. 6 and showing one of the devices for clinching the ear parts together after the coating has been applied thereto;

Fig. 12 is a vertical sectional view on the line 12—12 of Fig. 6 and showing the means for removing the connected ear parts from the turret;

Fig. 13 is a view partly in plan and partly in horizontal section showing the operating means 20 for the feeding devices, the control of the valve for the coating device, and the clinching means;

Fig. 14 is a view partly in section and showing more or less diagrammatically the control of the valve for the coating machine, and the means 25 for automatically closing the valve when the machine is stopped, and also the hand means for closing the valve while the machine continues to operate.

The invention has to do with a machine for 30 assembling the parts of an ear and the clinching of the same together so that they may be handled as a unit. The ear backs and the ear fronts are placed in hoppers and are fed from the hoppers through delivery chutes to a receiving tur-

ret which conveys the ear parts to the different stations where they are operated upon. The turret is provided with a series of pockets to receive the ear parts. First, an ear back is placed in the turret and then an ear front is fed on 40 to the ear back, and properly nested therein preparatory to the clinching of the parts together. The turret then presents the assembled ear parts to a coating machine where a

coating of sealing material is flowed on to the 45 ear back around the peripheral edge thereof and within the flange of the ear back. The turret then presents the assembled ear backs with the coating applied thereto to a clinching device which bends the upwardly projecting flange of 50 the ear back over the flared flange of the ear front so as to clinch the parts together and hold the same in assembled position, fully covering and protecting the coating that has been applied thereto. The turret next presents the assem-

5

10

15

20

25

30

35

40

45

50

55

bled ear parts with the coating thereon and clinched together to the discharge station, where they are positively removed from the turret and delivered on to a conveyor so that the assembled units with the sealing material thereon may be passed through an oven or other suitable means for setting or drying the coating.

Before proceeding with the description of the machine, the construction of the ear which is being formed will be briefly described. In Fig. 1 there is shown in cross section the ear front and ear back nested together preparatory to the coating of the same. The ear front 1 has an opening 2 therethrough for receiving the bail. The depending skirt of the ear front is provided with an outwardly flaring flange 3. The ear back 4 is free from openings and serves as a closing means for the opening 2. Said ear back has a channel formed near the peripheral edge thereof, and an upstanding flange 5. Fig. 2 shows the parts with the coating flowed on to the ear back and indicated at 6. Fig. 3 shows the parts after having been subjected to the clinching means which turns the flange 5 inwardly and over the flared flange 3 so as to unite the parts loosely, but sufficiently to hold them together as a unit. After the parts have been assembled and clinched together in the manner just described, then they are passed through an oven and the coating dried or set. This completes the assembled ear construction and it is ready for attachment to the pail. The wall of the pail indicated at 7 is provided with an opening to receive an ear inserted from the inside outwardly through the opening. Said peripheral edge portion around the opening is bent so as to provide an inwardly inclining flange 8. This flange is hooked into the flange on the ear back and forms therewith and with the flared flange on the ear front, a joint which is completely sealed by the sealing material placed on the ear parts. This operation is accomplished by a bumping of the ear parts after they are placed as shown in Fig. 4. In Fig. 5, a completed joint is shown, and it will be noted from this figure that the ear is attached to the container body through a joint which is hermetically tight and free from leakage of any character. This enables ears to be attached to pails which may be hermetically sealed, if desired.

The machine embodying the invention, as illustrated in the drawings, consists of a supporting base 9 which may be of any desired construction. Mounted on this supporting base is an upper frame structure 10. The upper frame structure 10 is provided with a supporting sleeve 11 in which is mounted a supporting column or standard 12. Mounted for rotation on the column 12 is a sleeve 13. Said sleeve is provided with a shoulder 14 and resting on said shoulder is a hub 15 carrying the turret 16. The turret 16 as shown in Fig. 6, is provided with a series of pockets 17 equally spaced from each other. Directly beneath the turret 16 is a supporting annular table or plate 18. The turret moves very close to the annular plate and will slide the assembled parts of the ear while retained in the pocket along the supporting plate from one operating station to another. Mounted on the supporting plate is an annular guide rail 19 which retains the assembled parts in the pockets in the turret.

Mounted in suitable bearings in the upper frame 11 of the machine is a vertical shaft 20. The vertical shaft 20 is in alignment with a driv-

ing shaft 21 and is connected thereto by a clutch 22 which may be of any desired construction. The shaft section 20 telescopes within the shaft section 21 and when the clutch 22 is in the position shown in Fig. 7, the two sections of the shaft are connected for rotation. When this clutch 22 is raised, then the two shaft sections are disconnected. The driving shaft 21 carries a bevel gear 23 meshing with a bevel gear 24 on the main actuating shaft of the machine. This shaft 20 carries a crank arm 25 provided with a roller 26 (see broken lines, Fig. 6). The roller 26 forms a part of a Geneva stop motion through which the turret is intermittently rotated step by step and brought to a stationary position where it is locked for an interval of time against movement. This is the usual construction and it will not be necessary to describe the operation in any great detail. The roller operates in radial slots 27 in the actuated member 28 of the Geneva stop motion. The segmental disk 29 carrying the arm 25 moves into locking engagement with the turret between the radial slots, in the usual way. The actuated member 28 is pinned to the sleeve 13 and causes the sleeve 13 to turn therewith. Mounted on the sleeve 13 and keyed thereto is a collar 30. This collar turns with the sleeve but can move endwise of the sleeve. Springs 31 normally press the collar in an upward direction as shown in Fig. 11, and this collar carries one or more projections 32 which are adapted to seat in recesses 33 in the hub 15 for driving the turret. The projection 32 has the faces thereof inclined, and if there occurs a jam in the parts being handled by the turret, the turret will stop and the collar 30 will be given an endwise movement through the inclined faces of the projections acting on the inclined faces of the recesses in which they seat.

Bearing on the under face of the projecting ledge 36^a of the collar 30 is a roller 34 carried by a lever 35 which is pivoted at 36. When the collar is pressed downward through a stopping of the movement of the turret, it will press downward on the roller 34 and lift the right-hand end of the lever 35. Attached to the free end of the lever 35 is a lug 37 which is adapted to contact with a lug 38 on an arm 39 attached to a shaft 40. The shaft 40 carries an arm 41 provided with a forked end carrying rollers 42 running in an annular groove 43 in the clutch member 22. A spring 44 is attached at 45 to the arm 41 and is attached at its upper end to a lug 46 carried by the upper frame. This spring normally tends to move the clutch so as to disengage the same from the driving shaft and stop the machine. When the clutch is thrown into engagement with the cooperating parts for driving the machine, the lever 35 is moved to the position shown in Fig. 7, so that the lug 38 will be engaged by the lug 37 and this will hold the clutch in engagement. The adjacent faces of the lugs 37 and 38 are inclined for the purpose of automatically permitting engagement of this control lever 35 with the lever 39 when the clutch is closed. A spring 41 attached to the control lever 35 normally urges the same downwardly at the free end, and causes said holding lugs to become engaged. It will be seen that when a jam stops the turret and forces the collar 30 downwardly, it will swing the control lever 35 so as to release the lever 39, and the spring 41 will shift the clutch so as to stop the machine.

As shown in the drawings, the feeding-in devices and also the operating devices are shown in

duplicate; that is to say, there are two feed chutes for simultaneously delivering ear backs to pockets in the turret. There are also two feed chutes for simultaneously placing ear fronts on the ear backs, 5 and then two separate coating devices and two separate clinching devices. The turret is moved by the means described above so as to place two adjacent pockets opposite the two feed chutes for feeding the ear backs thereto, and then the 10 turret is turned so as to place the two pockets containing the ear backs in proper register with the chutes for feeding the ear fronts into the pockets, and likewise, the turret is then turned for presenting the assembled ear parts to the respective 15 coating devices and the respective clinching devices. The ear backs are controlled by feeding devices which are similar in construction in connection with each feed chute. One of the feed chutes is indicated at 48 and the other at 49. These 20 feed devices being similar, will be described as one and like reference numerals applied to the other. The ear backs are fed into the chutes from hoppers which may be of any desired construction. The ear backs slide by gravity down the chutes 25 in a continuous row, contacting with each other. There is a feed dog 50 carried by a lever 51 pivoted at 52 which is urged by a spring 53 so that it contacts with the ear back and retards its movement in the chute. As shown in Fig. 7, this feed dog 50 30 is moved so as to engage the ear back 4' for preventing movement thereof in the chute. The ear back 4'' has been released and has moved forward into the pocket 17 of the turret 16. The lever 51 is provided with a depending lug 53a 35 which contacts with the table or plate 18 and positions the dog 50 so that it will engage the flange of the ear back for holding the same from movement. The dog 50 is secured to the lever 51 by a clamping sleeve and bolt 54 which permits 40 the dog to be shifted toward and from the turret and also vertically for properly setting the same.

There is a feed dog 55 spaced nearer the turret than the feed dog 50. This feed dog 55 is carried by an arm 56 which has a slot in its outer end and the feed dog 55 is connected thereto through a bolt and sleeve connection 57 which permits the same to be shifted toward and from the turret or raised and lowered. Mounted on the arm 56 is a bolt 58. This arm 56 is carried by a bracket 59 which has an up and down movement. When the bracket moves downward, the bolt 58 will contact with the right-hand end of the lever 51 and lift the feed dog 50. This same downward movement of the bracket will bring the dog 55 into position where it will stop the forward movement of the ear back 4'. The dog 50 is now over the next following ear back, and when the bracket is raised, the ear back 4'' will be released by the upward movement of the dog 55, and the next ear back will be stopped in its movement by the dog 50. It is understood that this bracket is of sufficient extent so that the feeding devices for the two chutes are simultaneously operated thereby, and this means that there will be an ear back released and fed forward by gravity into the pocket associated with each chute, and this occurs simultaneously.

The bracket member 59 is attached to a head member 60 carried by a column 61 mounted for vertical movement in a standard 62 carried by the upper frame. The head member is provided with an arm 63 carrying a pin 64 sliding in a sleeve carried by the arm 65 in the standard 62, and this will prevent the column from angular movement as it moves up and down. A lever 66 having a 70 forked end carrying rollers 67 engaging an annu-

lar groove 68 in a collar attached to the column serves as a means for raising and lowering the column. This lever 66 is pivotally supported on a shaft 69, and carries at its inner end a roller 70 running in a cam groove in a disk 71. The disk 71 is fixed to the cross shaft 72 which carries a worm gear 73 meshing with a worm gear 74 on the shaft 20 75 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

In Fig. 8 of the drawings, there is shown a feeding mechanism for controlling the ear fronts. There are two chutes 75 and 76 as shown in Fig. 1 for the ear fronts, which chutes are supplied with ear fronts from hoppers in any suitable way. Mounted beneath each chute is a control feed for the ear fronts. These feeds are similar in construction and only one will be described, although the numerals will be applied to each. There is a feed dog 77 mounted beneath the chute and moving upward through a slot in the chute into the path of travel of the ear backs 1'. The ear back 1' is shown as retained by the dog 77 and the ear back 1'' is bearing against the same. The dog 77 is pivoted at 78 to an adjustable supporting member 79 which is attached to the table or plate 18 by a bolt 80 passing through a slot 81 in the table. This permits the feed dog to be moved toward or from the turret for properly positioning the same. A feed dog 82 is located directly above the feed dog 77 and is pivoted at 83 to the supporting member 79. A spring 84 bearing on the feed dog 82 moves the same to a position beneath the floor of the chute so that the ear fronts will slide along said chute. The feed dog 82 carries a plate or roller 85 which bears on the feed dog 77 to the right of this pivot at 83, so that the spring will raise the feed dog 77 into a position for obstructing the movement of the ear backs.

It is desired that no ear front be fed into the pocket of the turret unless there is an ear back with which it may be assembled. A control means has been provided which renders the feed dogs inoperative if there is no ear back in the turret pocket. This control means consists of a pin 86 carried by an arm 87 supported by a sleeve 88 mounted for oscillation on the shaft 89. There is an arm 90 also attached to this sleeve, and a spring 91 bearing on the under face of the arm 90 normally swings the bell crank so as to move the pin 86 into the pocket in the turret, if the pocket is empty. When, however, there is an ear back in the pocket of the turret, then the pin 86 is limited in its movement by contact with the ear back. The means for operating the feed dogs is controlled by the position of this bell crank carrying the pin 86. Mounted on the head member 60 is a sleeve 92 carrying an upstanding arm 93. Said sleeve also carries a horizontal arm 94 which overlies the arm 90 of the bell crank carrying the pin 86. A spring 95 operates to yieldingly force the arm 94 against the arm 90. A stop screw 96 limits the downward movement of the arm 90 and this will position the upstanding arm 93 directly beneath the lever 77. When the column 61 is raised it will cause the arm 93 to engage the lever 77 and oscillate the same so as to release the ear front. If, however, there is no ear back in the pocket, then the spring 91 will raise the arm 90 and in so doing, will raise the arm 94 and move the upright arm 93 to a position so that it escapes the feed lever and no ear front is released on the upward movement of the head member 60. This does not, however, interfere with the operation of the feed which releases the ear backs.

From the above it will be apparent that a feed- 75

- ing mechanism has been provided for the ear backs and the ear fronts so that the pockets of the turret are provided with the ear backs, and when the pocket has an ear back therein, an ear front will be fed on to the same. This assembles the parts of the ear ready for the applying of the coating thereto. The turret is then turned to bring the assembled parts of the ear to the coating stations.
- 10 One of the coating stations is indicated at C in Fig. 6 and the other at C'. They are similar in construction, and only one will be described in detail. The column 12 extending up through the central part of the machine is stationary and carries the sleeve 97 at the upper end thereof. Said sleeve carries a projecting boss 98 which supports the bracket carrying the coating devices. The bracket is indicated at 99. Said bracket is pivoted to the boss by a pivot pin 100. The bracket is shown in Fig. 9 in operative position, and it is held in this position by a bolt 101 passing through openings in the bracket arms and through a projecting bracket 102 carried by the sleeve. The bracket 99 is in the form of a cross head 103 carrying two forwardly extending and downwardly inclining arms 104. Attached to each arm is a coating nozzle 105. A supply pipe 106 leads from the nozzle to a mounting in the arm 104 and a flexible pipe 107 is attached thereto for supplying coating to the nozzle. There is, of course, a supply pipe 107 for each coating nozzle, and these supply pipes extend to the sleeve 97 at the top of the column and are connected to a feed pipe shown in dotted lines at 108 which extends downwardly through the column to the base of the machine. The base of the machine has a suitable supply pump for feeding the coating material to the nozzles. The nozzle 105 is so disposed that it is directly above the pocket in the turret when the turret comes to rest at the coating station.
- 45 The table or plate 18 is provided with an opening 109 in which is located a chuck 110. The chuck 110 has a recess in its upper face adapted to conform to the shaping of the backing, and the turret moves the assembled ear parts directly over the chuck, so that the ear back will fall into said recess. The chuck is rotating continuously and it is intermittently raised so as to lift the assembled parts of the ear from the pocket into contact with a gravity held centering rod 111. This rod engages the ear front at the opening therein and will serve to center the ear front on the ear back and also guide the assembled parts during the 50 rotating of the parts through the rotating of the chuck. In other words, this centering rod is free to rotate and will hold the parts through the weight thereof, in contact with the chuck so that the chuck will rotate the parts. As shown in Fig. 6, the ear parts are raised to the dotted line position and rotated, and in this position the nozzle 105 is directly above the channel in the ear back, and directly over the outwardly flaring flange of the ear front. The valve of the coating device is 55 opened, and a jet of coating material is forced from the nozzle on to the assembled ear parts. This will form a coating at the peripheral edge portions of the ear parts all the way around the ear.
- 60 The chuck is mounted for rotation in the upper frame and carries an elongated pinion 112. This pinion meshes with a pinion 113 on a stub shaft 114, and the pinion 113 in turn meshes with a pinion 115 attached to the sleeve 116 which is 65 mounted for free rotation on the column 2 (see

Fig. 11). The sleeve carries a gear 117 which meshes with a pinion 118 on the shaft 20. Thus it is that the chuck is rotated from the shaft 20. The chuck is moved endwise by a lever 119 which is pivotally mounted on the bracket 120. Said lever carries a yoke end 121 provided with rollers engaging an annular groove 122 in a collar 123 carried by a member 124 that can slide vertically. The shaft 125 which carries the chuck 119 bears on the collar 123 so that when the collar is raised, the chuck is raised, and when the collar is lowered, the chuck will be lowered. The lever 119 carries a roller 126 running in a groove in a disk 127 fixed to the shaft 12.

10 The flow of the sealing material through the nozzle 105 is controlled by a needle valve 128. This needle valve is held closed by means of a spring 129 and is opened by a control lever 130. This control lever 130 is pivoted at 131 to the bracket 99. An adjustable stop bolt 132 limits the downward movement of the lever, but is so positioned that the spring will close the valve. The levers 130 controlling the two nozzles are simultaneously operated for opening the valves through the following mechanism. A shaft 133 is mounted in bracket arms 133^a, 133^b carried by the cross head 103. Attached to the shaft is an arm 134 to which a spring 134^a is attached, and this spring normally tends to turn the shaft in a clockwise direction as viewed in Fig. 9. Also 20 attached to the shaft 133 is an arm 135, which carries a rod 136. Said rod is threaded into the arm for adjustment and is held in set positions by a lock nut 137. When this rod 136 and the arm 135 are raised then the shaft 133 is turned in 30 a counterclockwise direction as seen in Fig. 10. The rod 136 bears on the upper end of a rod 136^a which is raised and lowered by mechanism which will be hereinafter described.

Attached to the shaft 133 is a bracket 138 (see 40 Fig. 9). There is a similar bracket and associated parts for the control lever operating the farther nozzle. As these parts are all similar it will only be necessary to describe in detail those shown in Fig. 9. Said bracket arm 138 is provided with a recess in which is located a control block 139. A spring 139^a located between the control block and the bracket arm 138 normally forces the block to the limit of its movement to the right as viewed in Fig. 9. The block 139 rests on the bracket arm. Extending along each side of the control block 139 are bars 140, 140. A pin 141 is fixed to the control block 139 and extends through slots 141^a in the bars 140, 140. These bars are held mounted to rock in different 50 positions and this is the means which limits the movement of the control bar 139 to the right as viewed in Fig. 9. Pivoted attached to the control lever 130 is an upwardly extending member 142. Said member extends into a recess in the 60 control lever and is carried by a pivot pin 142^a. Said member is provided with a shiftable plate 143 which is secured to the member 142 by suitable bolts which permit said plate to move endwise in said member. The bolt 143^a is threaded into the plate 143. This bolt extends through a laterally projecting extension of the member 142. The bolt is held from endwise movement in said extension by suitable collars and is provided with a slotted head whereby it may be turned for changing the set position of the plate 143. A spring 145 carried by the control lever 130 abuts against the member 142 or turns the same in a clockwise direction against a stop 145^a.

70 The rod 111 is provided with collars 111^a. The 75

member 142 is provided with a cam face 142^b. When the rod 111 is raised the collar engages this cam face and will shift this upright 142 so as to place the plate 143 over the control block 139.

5 Normally this plate 143 is so positioned that the control block 139 if raised will not engage the plate. When the ear parts are in position for being coated the chuck lifting the ear parts lifts the rod 111 and this will throw the plate 143 into range of movement of the control block 139 and the control block 139 will lift through this member 142 the control lever 130 and open the valve. Thus it is that the valves are opened intermittently through the raising and lowering of the 10 control block 139, but unless these are ear parts to be coated the valves will not be opened.

The control block 139 is raised and lowered through the oscillations of the shaft 133. The rod 136^a rests on a lever 162 which is pivoted to the frame. The lever carries a roller 163 which cooperates with a cam 164 on the shaft 72. As the shaft rotates the lever will be raised and lowered and this will oscillate the shaft 133 lifting and lowering the control block 139, thus raising and lowering the control lever 130 which in turn will raise the needle valve allowing the coating material to be discharged on the rotated ear parts and after sufficient coating material has been applied to the ear parts then the cam 164 15 will permit the block to be lowered and the valve to close. The spring 165 closes the valve and the control lever opens the valve.

There are times when it is desirable to stop the flow of the coating material. The bars 140 are 20 connected to a block 146^a. The bars are guided in their back and forth movement by a suitable guide bracket 140^a. There is a rod 146 connected to each block and these rods are in turn connected to a cross bar 147 which is pivoted 25 at one end of a rock lever 148. The rock lever is pivotally mounted on the sleeve 97. A rod 149 connects this rock lever 148 to a second rock lever 150 pivoted at 151 to a bracket 152 carried by the frame (see Fig. 14). A spring 153 attached 30 to the rock lever 150 and to the frame normally turns said rock lever 150 in a clockwise direction which will push on the rod 149 and turn the rock lever 148 so as to pull on the rods 146. This permits to be moved the pin 141 to the limit of 35 its extent of movement to the right as viewed in Fig. 9. In this position the control block 139 is moved so that it will be engaged by the plate 143 provided there are ear parts to be coated.

In case of a jam the latch lever 35 is moved so 40 as to release the lever arm 39 and the spring 44 will then separate the clutch members 22 and stop the machine. The arm 39 moves in a clockwise direction when this occurs. Carried by the arm 39 is a plate 155 which bears on a block 156 45 attached to a rod 154 which in turn is attached to the rock lever 150. When this arm 39 is moved in a clockwise direction for releasing the clutch it will pull down on the rod 154 which will oscillate the rock lever 150 in a counter-clockwise direction. This movement of the rock lever 148 pushes on the rods 146 and through the pin 141 will shift the control block 139 to the left 50 as viewed in Fig. 9. The spring 139^a yields to permit this shifting of the control block 139. The control block 139 is now positioned so that even 55 if there are ear parts to be coated and the upright 142 shifted to the left as viewed in this figure, still it will not be in range of the control block 139 and therefore the lever 130 will not be lifted and the valve will not be opened.

While the clutch 22 when separated will stop the operation of the machine, this is not the main clutch for the actuation of the machine. There is a main clutch controlled by the shaft 158 and the hand lever 157. The operator on shifting this hand lever can stop the machine at will. Attached to and moving with the hand lever 157 is an arm 159 which overlies a block 161 attached to the rod 160. This rod is attached at its upper end to the rock lever 150. The hand lever 157 is moved in a counterclockwise direction in order to open the main clutch and this will turn the rock lever 150 in a counterclockwise direction and pull on the rod 149 and through the parts connected thereto will shift the control bar 162 in the manner above described so as to cut off the operation of the valve releasing mechanism. When the machine is stopped at the will of the operator or in case of a jam, the control lever is at once released and the valves will close. This 20 avoids stopping the machine with the control 25 lever 164 positioned so as to leave the valves open.

Whenever it is desired to obtain access to the assembled ear parts at the coating stations, the bracket 99 may be released by withdrawing the bolt 101 and this will release the bracket so that it, with all the parts supported thereby, may be raised. The flexible tubes supplying the coating material to the nozzles permits this lifting of the 30 bracket.

After the assembled ear parts have been supplied with the coating material, the chuck is lowered so as to again place the ear parts in the pockets of the turret and the turret is turned through another step movement so as to bring the ears to the bumping stations where the flange of the ear back is bent so as to loosely clinch the parts together. The bumping stations are indicated at B and B'. They are similar in construction. Mounted on the upper frame 10 is a bracket 167 carrying at its outer end a sleeve 168 which overhangs the turret. Mounted in this sleeve is a die clinching member 169. Said die clinching member has a shank portion 170 extending through the sleeve and abutment collars 171 and 172 are attached to said shank portion for holding the same in a fixed position in the bracket. The die clinching member has a recess 173 in its under face which is provided with a tapered clinching wall 174. Located centrally of 35 the stem of the die and projecting into the recess is a stripper rod 175. A spring 176 yieldingly presses this rod downward. Beneath the table or plate 18 is a plunger 177 which is normally substantially flush with the upper face of the table, and when the turret moves the ear parts over this plunger, the ear back will be seated in a recess in the plunger. The two plungers of the adjacent clinching devices are carried by cross head 178 which is mounted on a supporting rod 179, and the rod is raised and lowered by means of a lever 180 which is forked and carries rollers running in an annular groove formed in a collar 181 attached to the rod 179. When the lever 180 is raised at its free end, the plunger 177 will lift the assembled parts of the ear, bringing the same into contact with the stripper rod 175, lifting said rod, and carrying the ear front up into the recess 173. The inclined face of the die clinching member will contact with the flange of the ear back and turn the same over the flared flange of the ear front, thus clinching the two parts loosely together, so that they may be handled as a unit. The plungers 177 then drop, placing the ear units 40 in the pockets of the turret so that they may be 45 50 55 60 65 70 75 80 85 90 95

conveyed to the discharge station. The lever 180 is mounted on a stub shaft 182 carried by a bracket 183 on the base of the machine (see Fig. 13). The lever carries a roller 184 running in a cam groove in a disk on the shaft 72.

The turret is then moved through another step movement and brings the ear parts to the discharge station. The cross head 178 beneath the clinching station extends around underneath the discharge station. Mounted on the cross head at the discharge station is a lifting plunger 185. There are two of these plungers which move up into the pockets of the turret and raise the clinched together ear parts preparatory to the discharging of the same from the machine. Traveling alongside of the path of movement of the turret is a conveyor belt 186. Said conveyor belt moves along a support 187 having an up-standing flange 188. This support is carried by a bracket 189. Mounted on the upper frame is a bracket 190 which extends above the turret and carries an overhanging arm 191. In the arm 191 is mounted a shaft 192 carrying a gear wheel 193 meshing with a gear wheel 194 carried by a cross shaft mounted in the bracket 190. This cross shaft is driven by a sprocket chain 195. Mounted on the shaft 192 is a head 196 which rotates with the shaft. Said head is provided with radially extending recesses in each of which is mounted a radially moving blade holder 197. The blade holder is spring pressed outwardly away from the shaft by springs 198. Each blade holder carries a flexible wiper 199. Also mounted on the blade holder is a roller 200. There is a roller at each end of the blade holder. Attached to the bracket 190 is an arm 201 having a cam-shaped face 202 with which the rollers 200 alternately contact. When the shaft 192 is rotated in the direction of the arrow in Fig. 12, the wiper will follow the path indicated by the broken line. Just before the wiper passes over the pocket in the turret, it is moved radially inwardly and thence outwardly so that the end of the wiper travels in substantially a straight line across the upper face of the turret, and this will sweep the assembled ear parts from the plungers 185 on to the conveyor belt 186. The conveyor belt carries the assembled ends into an oven or other suitable means where heat may be applied to the coating for setting or drying the same.

It is thought that the operation of the machine will be obvious from the detail description given above. The ear backs and the ear fronts are assembled in the pockets of the turret and are presented first to the coating devices, thence to the clinching devices, and finally to the discharge station where they are removed from the machine. While the machine has been shown as having two feeding-in stations and two operating devices, it will be understood, of course, that the number of operating devices may be increased or decreased, as desired.

It is obvious that the machine may be readily adjusted to accommodate different size of ear parts, and that it is fully automatic and will continue to operate unless automatically stopped through a jam of the parts or through the action of the operator. When the parts are restored to their normal position, the clutch 22 is automatically closed through the action of the spring 153. There is, of course, a main clutch between the main shaft carrying the gear 24 and the main driving means for the machine, which is independently controlled, and through which the machine may be manually stopped or started, when-

ever desired. It cannot be started, however, when there is a jam in the parts, until the jam has been released and the clutch 22 closed.

Having thus fully described my invention, what I claim as new and desire to secure by Letters Patent, is:—

1. An ear assembling machine comprising a conveyor having means for receiving ear parts, means for feeding an ear back into the receiving means, means for feeding an ear front onto said ear back in the receiving means, means for applying a coating to the assembled ear parts in the receiving means, means for clinching said parts together, and means for intermittently moving said conveyor for presenting the receiving means in succession to the ear back feeding means, ear front feeding means, coating means, and clinching means.

2. An ear assembling machine comprising a rotating turret having pockets for receiving ear parts, means for feeding an ear back into a pocket, means for feeding an ear front onto the ear back in the pocket, means for coating the assembled ear parts in said pocket, means for clinching said parts together, and means for intermittently rotating said turret for presenting the pocket in succession to the ear back feeding means, the ear front feeding means, the coating means, and clinching means.

3. An ear assembling machine comprising a rotating turret having pockets at the periphery thereof shaped to receive and convey ear parts, means for simultaneously feeding ear backs into two of said pockets, means for feeding simultaneously ear fronts onto the ear backs in said respective pockets, two coating devices spaced from each other the distance between two pockets, and means for intermittently rotating said turret through an angular movement twice the extent of the angular distance between two pockets for presenting the pockets to the ear back feeding means, the ear front feeding means, the coating devices and the clinching devices.

4. An ear assembling machine comprising a rotating turret having pockets at the periphery thereof for receiving ear parts, means for feeding an ear back into said pocket, means controlled by the presence of an ear back in a pocket for feeding an ear front onto the ear back in the pocket, a coating device, a clinching device, and means for intermittently rotating said turret for presenting a pocket in succession to the ear back feeding means, the ear front feeding means, the coating means, and the clinching means.

5. An ear assembling machine comprising a rotating turret having a pocket at the periphery thereof for receiving ear parts, means for feeding an ear back into said pocket, means for feeding an ear front onto said ear back in said pocket, said last named means including a control finger adapted to contact with an ear back in the pocket for rendering the ear front feeding means operative whereby if there is no ear back in the pocket no ear front will be released and fed into the pocket, a clinching device, a coating device for applying coating to the ear parts, and means for intermittently rotating said turret for presenting the pocket in succession to the ear back feeding means, the ear front feeding means, the coating device, and the clinching device.

6. An ear assembling machine comprising a rotating turret having pockets at the periphery thereof for receiving ear parts, mechanism for placing ear back and ear front in said pockets assembled for clinching, a coating device, a clinch-

ing device, and means for intermittently rotating said turret for presenting the pockets in succession to the ear back and ear front placing mechanism, the coating device, and the clinching device.

5 7. An ear assembling machine comprising a rotating turret having pockets at the periphery thereof for receiving ear parts, mechanism for placing ear backs and ear fronts in said pockets assembled for clinching, a coating device, a clinching device, a take-away device, and means for intermittently rotating said turret for presenting said pockets in succession to the ear back and ear front placing mechanism, the coating device, the clinching device, and the take-away device.

10 8. An ear assembling machine comprising a coating means, mechanism for assembling ear backs and ear fronts and presenting the same to the coating means, said coating means including a rotating chuck, a nozzle associated therewith, a valve for controlling the nozzle, a spring for closing the valve, a control lever for opening the valve, means controlled by the presence of ear parts to be coated for actuating said control lever, means for stopping the machine, and means controlled by the stopping means for releasing the valve so as to permit the spring to close the same.

15 9. An ear assembling machine comprising a rotating turret having pockets at the periphery thereof for receiving ear backs and ear fronts in assembled relation, a clinching device for clinching the parts together, a take-away device including a rotating member above the turret, radial arms carried by said rotating member, yielding means for forcing said arms outwardly, and a stationary cam operating on said arms and shaped so as to cause the arm to move in substantially a straight path across the upper face of the turret while ejecting the ear parts from the turret.

20 10. An ear assembling machine comprising a rotating turret having pockets adapted to receive ear parts in assembled relation, a coating device associated with the valve for coating said ear parts, a clinching device associated with said turret for clinching the ear parts together, a take-away device including a rotating member having a radial arm, means for yieldingly moving the arm outwardly, a stationary cam contacting with the arm causing the lower end thereof to move in substantially a straight path at a uniform distance above the turret for ejecting the ear parts therefrom.

25 LOUIS BURCKLE.
